ELECTRIC DISCHARGE TUBE

John Walter Ryde, London, England, assignor to
The General Electric Company Limited, Lon-
don, England

Application May 29, 1934, Serial No. 728,101
In Great Britain April 4, 1933

3 Claims. (Cl. 176—122)

This invention relates to electric discharge tubes of the type in which all parts of the tube have to be maintained above some temperature greatly exceeding atmospheric, in order that the vapour pressure of some substance contained in it may attain a desired value.

In such tubes the portions most likely to fail to attain the requisite temperature are the ends, and especially the ends behind the electrodes. Many methods of heating the ends have been described; some of these involve metal sleeves outside the tube. The object of the invention is to provide an improved method of heating these ends.

According to the invention, an electric discharge tube of the type specified comprises a hollow metal body within the tube, not being an electrode of the discharge, fitting the end wall of the tube closely over a substantial part of its surface, so shaped and extending so far into the region between the main electrodes that one part of the body receives heat from the discharge and communicates it by conduction to those parts that fit closely the end wall of the tube whereby the said end wall is heated.

It is necessary for this purpose that some part of the said metal body should extend into the space between the electrodes that carry the discharge during the operation of the tube. For otherwise they will not receive any substantial amount of heat from the discharge. Thus the metal cases 12, 13 of Figure 1 of British Patent specification No. 392,509 are not metal bodies according to the invention, for while they extend into the space between the auxiliary electrodes, they do not extend into the space between the main electrodes 4, 5.

Certain embodiments of the invention will now be described with reference to the accompanying drawing, in which Figure 1 shows in section a discharge tube and Figures 2, 3 and 4 show in section the end portions of modified discharge tubes containing these embodiments. In all figures 1 represents the wall of the tube, 2 an electrode at this end, 3 the hollow metal body according to the invention, 4, 4' apertures in the end of the metal body nearest the end of the tube, through which pass leads 5, 5' to the electrode 2, these leads being out of contact with the metal body 3.

In Figure 1 the end wall of the tube is substantially the hemi-spherical end of a cylinder. The metal body 3 is then a sleeve the whole of whose exterior surface closely fits the interior of the hemispherical end wall. It must be so long that it reaches a part of the tube adequately heated by the discharge.

In Figure 2 the end wall of the tube is composed of two parts, one being narrower than the remainder of the tube. The sleeve now fits closely the narrow part as in Figure 1, but projects into the wider portion and is furnished with a collar 6, extending into the wider portion which fits the connecting wall closely in the region where the change of diameter occurs; for this region is apt to be one of relatively low temperature.

If the discharge is of the constricted type and most of it occupies an area of the cross section of the tube much less than the whole, the modification of Figure 1 shown in Figure 3 may be adapted. Here the end of the sleeve which is open in Figure 1 has portions 7 turned inwards, so that it lies in the region of the discharge from which most heat is to be derived, while the remainder of the body fits closely the end wall of the tube.

It is preferable that the metal body should extend further into the space between the electrodes than is shown in the drawing.

By an obvious modification Figure 4 is reached, where there is no sharp distinction between the portion turned inwards and the remainder, part of the body being a cone tapering towards the centre line. This form is appropriate when the only part of the tube that requires to be heated is the extreme end.

The exterior surface of the metal body in any of Figures 1, 2, 3 and 4 and in any other arrangements according to the invention is preferably polished, so that little heat is lost by radiation; its interior surface is preferably blackened so as to absorb radiant heat from the discharge.

I claim:—

1. An electric discharge tube comprising an envelope, a pair of main discharge electrodes arranged within the envelope, leads passing through the envelope to the electrodes, a vaporizable substance within the envelope and a hollow metal body fitting closely the interior of the end wall of the envelope adjacent to one of the electrodes and out of contact with the leads so that it will not act as an electrode, said body having a part extending into the region between the electrodes so as to intercept heat from the discharge, the heat being conveyed through the metal body and the portion closely fitting the end wall to heat the latter.

2. An electric discharge tube comprising an envelope, a pair of main discharge electrodes arranged within the envelope, leads passing through the end walls of the envelope to the electrodes, a vaporizable substance within the envelope and a hollow metal body adjacent to one of the elec-

- trodes and fitting closely the interior of the wall through which said leads pass, said body being provided with holes to space it from the leads so that it will not act as an electrode, said body 5 having a part extending into the region between the electrodes so as to intercept heat from the discharge, the heat being conveyed through the metal body and the portion thereof closely fitting the end wall to heat the latter.
- 10 3. An electric discharge tube comprising an envelope, a pair of main discharge electrodes arranged within the envelope, leads passing through the envelope to the electrodes, a vaporizable sub-

stance within the envelope and a hollow metal body fitting closely the interior of the end wall of the envelope adjacent to one of the electrodes and out of contact with the leads so that it will not act as an electrode, said body having a part 5 extending into the region between the electrode so as to intercept heat from the discharge, the heat being conveyed through the metal body and the portion closely fitting the end wall to heat the latter, said body being polished on its exterior 10 surface and blackened on its interior surface.

JOHN WALTER RYDE.
